(57) **CLAIM**

I claim the ornamental design for a holiday ornament with magnet, as shown and described.

DESCRIPTION

FIG. 1 is a front view of a first embodiment of a holiday ornament with magnet showing my new design;

FIG. 2 is a rear view thereof;

FIG. 3 is a right side view thereof; the left side view is a mirror image of the right side view;

FIG. 4 is a top view thereof;

FIG. 5 is a bottom view thereof;

FIG. 6 is a front, right side perspective view thereof;

FIG. 7 is a front view of a second embodiment of a holiday ornament with magnet showing my new design; the rear view is identical to the front view;

FIG. 8 is a right side view thereof; the left side view is identical to the right side view;

FIG. 9 is a top view thereof;

FIG. 10 is a bottom view thereof;

FIG. 11 is a bottom, right side perspective view thereof;

FIG. 12 is a front view of a third embodiment of a holiday ornament with magnet showing my new design;

FIG. 13 is a rear view thereof;

FIG. 14 is a right side view thereof; the left side view is a mirror image of the right side view;

FIG. 15 is a top view; and,

FIG. 16 is a bottom view thereof.

The broken line showing of a hanger is included for the purpose of illustrating environment and forms no part of the claimed design.
